CARROLL J. SHERMAN, OF HOUSTON, TEXAS, ASSIGNOR OF ONE-THIRD TO EWING WERLEIN AND ONE-SIXTH TO CHARLES H. SHERMAN, BOTH OF HARRIS COUNTY, TEXAS

LIQUID AND GASEOUS FUEL BURNER

Application filed February 21, 1928. Serial No. 255,872.

My invention relates to burners and pertains particularly to installations for employing both liquid and gaseous fuel.

My burner is particularly adapted for use in heaters and may be used in small household heaters or for larger commercial furnaces either singly or in tandem.

It is an object of the invention to produce a burner which may be used with liquid fuel with connections arranged so that gaseous fuel may be used either simultaneously or alternately with the liquid fuel. Provision is also made whereby the gas and liquid fuel feeding devices are separated so that no oil will interfere with the effective feed of the gas, yet the gaseous fuel may be used to heat up the vaporizer for the liquid fuel.

Means are also provided to deflect the air from a forced draught away from the vaporizer so that the vaporizer will not be unduly cooled.

It is also desired to provide means for igniting the fuel at any time by the use of a pilot light.

Referring to the drawings herewith, Fig. 1 is a central vertical section through a burner employing my invention. Fig. 2 is a vertical section of a burner taken on the plane 2-2 of Fig. 1. Fig. 3 is a transverse section of the burner structure taken on the plane 3-3 of Fig. 2. Like numerals of reference are employed to designate like parts in all the views.

The present invention is an improvement on the burner shown and described in my prior Patent No. 1,625,961, granted April 26th, 1927. In carrying out my invention I provide a base member 1 which comprises an approximately cylindrical hollow member having side walls 2, the lower end being closed by the lower wall 3. The upper end of the cylindrical portion of the body is connected at 4 with a flaring bowl-shaped plate 5, which extends upwardly to provide an enclosing wall about the lower part of the burner which may act as a combustion chamber, as will be later described. The lower portion of the combustion wall adjacent the cylindrical member 2 is curved downwardly to provide a

groove or channel 6 to receive the liquid fuel which may drip therein.

Centrally of the base member 1 is an upwardly extending tubular supporting member 7. As shown in Fig. 3, this supporting member is oblong in shape so as to form an enclosure about the fuel feeding tubes. The lower wall of the tubular support 7 is a solid member having a central channel 8 therethrough to receive a fuel pipe 9. Said fuel pipe projects below the channel 8 in the base and is threaded for engagement with an L-shaped coupling 10. Said coupling in turn is supported by a post 11 which is threaded for engagement with the supporting plate 12 upon the coupling. It will be obvious that by rotating the post 11, the height of the burner within the combustion chamber may be regulated. The coupling 10 is connected with an inlet pipe 13 connected with some source of supply of gaseous fuel, not shown.

Above the lower end of the tubular support 7 the support is recessed to provide a central chamber, indicated at 14 in Fig. 3. This chamber has on each side of the fuel conducting tubes, openings 15 extending from the base upwardly and adapted to allow the extension therethrough of fuel pipes. At one side of the center a pipe 16 is extended upwardly through the opening 15 and is perforated at 17 to allow the outlet of gas and is intended to form a pilot light, the gas being ignited and allowed to burn constantly to provide a flame whereby the fuel may be ignited.

Connected about the pipe 9 is a tubular stem 18 which has at its upper end a flaring dome-shaped generator plate 19, said plate being preferably formed integrally with the stem. The lower end of the stem is connected to the fuel inlet pipe 9 by a threaded connection, thus providing a space or chamber 20 between the fuel pipe 9 and the hollow stem 18 of the generator plate. This space allows for the passage of liquid fuel.

The liquid fuel pipe 21 is extended upwardly through the opening 15 and is connected with a lateral boss or extension 22 upon the stem 18 of the generator plate and connects with a passage 23, which in turn

connects with the annular space 20 between the gaseous fuel pipe 9 and the stem.

The generator plate 19 is curved outwardly and downwardly on its lower side and on its upper side is also curved outwardly and downwardly but has a groove or channel 24 extending circumferentially around the upper surface about midway between the outer margin and the central fuel opening.

10 Above the generator plate 19 is a vaporizer cap 25. This cap is an inverted cup-shaped plate approximately circular in outline. It is spaced from the generator plate by means of spacing lugs 26 formed on the lower side 15 of the cap, at spaced intervals, said lugs being adapted to rest upon the outer margin of the generator plate, as shown in the drawing. The generator cap conforms in outline closely to the contour of the plate, but 20 it is somewhat more elongated so as to provide a chamber or space 27 between the plate and the cap wherein vaporization of the liquid fuel may take place.

The space or chamber 27 is large enough 25 to accommodate the upper end of the gaseous fuel pipe 9 which extends above the opening in the generator plate and has at its upper end an annular disc or plate 29 secured thereon, which acts as a baffle above the outlet for the liquid fuel, preventing any chance 30 of the liquid fuel entering the upper end of the gaseous fuel pipe, as will be obvious. The lower rim of the disc is curved downwardly to a slight extent so as to deflect any 35 oil or other similar fuel issuing from the oil outlet.

The disc 29 also serves as a seat for a valve 40 which is a disc like plate having its lower margin extended downwardly to form a flange resting upon the baffle 29. Centrally 45 of the valve plate is a guide member 31 which extends into the upper end of the pipe so as to assure the proper seating of the valve which is adapted to be closed by gravity.

45 The lower end of the vaporizer cap is curved upwardly at 32 and a slight marginal space 33 is formed between the generator plate and the cap wherein combustion may take place in such a manner that the draught 50 of air past the combustion space will not blow out the flame.

The upper end of the wall 7 about the fuel pipes is preferably grooved to receive a deflector ring 35. Said ring fits with the upper 55 end of the wall 7 and has its upper end flared outwardly so as to direct the draught of air which is employed in the operation of the device, away from the generator plate so as to prevent the cooling of said plate. 60 This deflector is removable, as will be obvious from the drawing, and allows the parts to be more easily constructed and assembled.

At one side of the wall 2 of the base is an 65 opening 36. This opening is connected with a flow pipe 37 through which air may be

forced under pressure to the burner. I have shown as connected with the said pipe a blower 38 of ordinary construction, but it is to be understood that any type of blower may be employed which is effective in directing a current of air to the chamber within the walls of the base sufficient in amount for the purposes of combustion of the fuel. The blower 38 is shown as mounted upon upright posts 39 which are supported upon the plate 70 40, and this plate 40 in turn is supported upon a post 41 upon which said plate may be adjusted vertically in the manner shown.

The groove or channel 6 at the lower side of the combustion plate is connected at one point with a downwardly extending opening 42 which leads to an outlet pipe 43 whereby the excess liquid fuel may be drained from the burner.

In the operation of my device, the gaseous 75 fuel is preferably turned on first so as to feed the gas upwardly through the pipe 9, raising the valve 30 from its seat and allowing the gas to flow outwardly from between the generator plate and vaporizer 80 cap through the opening 33. The pilot light 16 will ordinarily have sufficient gas to produce a flame which will pass upwardly around the deflector 35 and from thence around the lower margin of the generator plate into the 85 combustion chamber and will ignite the gaseous fuel as it issues into the space 33 between the plate and cap. Combustion will then take place within the combustion chamber provided within the bowl 5. When the 90 generator plate and cap have been properly heated through the use of the gas the fuel oil may be then turned on. I contemplate using any ordinary type of fuel oil, whether 95 of light or heavy gravity, and the oil fed 100 inwardly through the pipe 21 will pass into the space 20 and will issue at the upper end of the generator plate and flow outwardly into the groove 24 and down the face of the generator plate to issue into the combustion 105 space. During its passage over the plate it will be submitted to high temperature formed by the combustion of the gas and will be 110 itself vaporized and will issue in that form in a highly combustible condition so that 115 an intense heat will be obtained. When the oil has been properly ignited and its vaporization has been thus provided for, the 120 gas may be reduced in amount, or if desired, may be entirely cut off. It is within the contemplation of this invention to use the two 125 types of fuel simultaneously where desired, and also either fuel may be used alone independent of the other. The arrangement, 130 however, whereby they may be used simultaneously is an extremely valuable one in that a combination of the two types of fuel may be made by the adjustment of the feed 135 of the gas so that a flame of the proper in-

tensity may be produced with little difficulty.

The forced draught which I have provided by the use of a blower assures the supply of the proper amount of air for combustion, and it will be obvious that this supply of air through the blower may be increased or decreased, according to condition, by varying the rate of rotation of the blower. The deflector which is employed to deflect the draught away from the lower side of the generator plate has the effect of drawing the air into the combustion space and prevents the cooling of the generator plate through the cold air entering through the blower. It will be obvious that the device here shown and described may be easily assembled or disassembled for cleaning or repairing and that the device may be made strong and durable and will last for long periods of time without replacement.

Having thus described my invention, what I claim as new is:

1. A fuel burner comprising a generator plate having a lower hollow stem and a central opening, a pipe for gaseous fuel extending upwardly through said stem and opening, and projecting above said plate, a liquid-tight connection between said stem and said pipe, means to feed fuel to said stem, means to conduct gas to said pipe, and a vaporizer cap spaced slightly above said generator plate.

2. A fuel burner comprising a generator plate having a lower hollow stem and a central opening, a pipe for gaseous fuel extending upwardly through said stem and opening, and projecting above said plate, a radial disc on said pipe above said plate forming a baffle, a liquid-tight connection between said stem and said pipe, means to feed fuel to said stem, means to conduct gas to said pipe, and a vaporizer cap spaced slightly above said generator plate.

3. A fuel burner comprising a generator plate having a lower hollow stem and a central opening, a pipe for gaseous fuel extending upwardly through said stem and opening, and projecting above said plate, a radial baffle on said pipe, a valve plate normally closing the upper end of said pipe, a liquid-tight connection between said stem and said pipe, means to feed fuel to said stem, means to conduct gas to said pipe, and a vaporizer cap spaced slightly above said generator plate.

4. A burner having a generator plate, a vaporizer cap spaced slightly from said plate to form a vaporizing chamber, said plate having a liquid fuel passage discharging thereon, a gaseous fuel pipe extending upwardly through said passage, a baffle on said pipe within said chamber, a valve normally closing the upper end of said pipe, and means to ignite the fuel about the outer margin of said plate.

5. A burner having a generator plate, a vaporizer cap spaced slightly from said plate to form a vaporizing chamber, said plate having a liquid fuel passage discharging thereon, a gaseous fuel pipe extending upwardly through said passage above said plate, and means to keep said plate heated when said burner is not in use and to ignite the fuel when the starting of said burner is desired.

6. A burner including a generator plate, a vaporizing cap spaced above said plate forming a vaporizing chamber between them, means to discharge both liquid and gaseous fuel simultaneously into said chamber, and means to ignite said fuel.

7. A burner including a generator plate, a vaporizing cap spaced above said plate forming a vaporizing chamber between them, a liquid fuel tube discharging through said plate, a gaseous fuel pipe extending above said plate into said chamber, means to prevent the liquid fuel from entering said gaseous fuel pipe and means to ignite said fuel.

8. A fuel burner adapted for either liquid or gaseous fuel including a liquid fuel conducting tube, a generator plate on the upper end thereof, a pipe concentric with said tube for gaseous fuel, a vaporizer cap above said plate, said cap and plate being spaced at their margins to form a combustion space and means to force a draught of air past said combustion space.

9. In a fuel burner for either liquid or gaseous fuel the combination of a generator plate, a vaporizer cap, means to feed both gaseous fuel and liquid fuel into the space between said plate and cap, means to ignite said fuel and means to force a draught of air past said plate.

10. In a fuel burner, a base chamber, a hollow stem therein, a generator plate on said stem, a pipe for gaseous fuel extending upwardly through said base chamber and said stem, said pipe having a threaded connection with said stem, a vaporizer cap spaced above said plate to form a vaporizing chamber, means to feed liquid fuel to said stem, and a valve in said chamber normally closing the upper end of said pipe whereby either liquid or gaseous fuel may be burned.

11. In a fuel burner, a base chamber, a hollow stem therein, a generator plate on said stem, a pipe for gaseous fuel extending upwardly through said base chamber and said stem, said pipe having a threaded connection with said stem, a vaporizer cap spaced above said plate to form a vaporizing chamber, and means to feed liquid fuel to said stem, whereby either or both liquid or gaseous fuel may be burned.

12. In a device of the character described adapted to burn either liquid or gaseous fuel, a pair of concentric fuel passages, means to deflect the fuel from each passage, a vaporiz-

ing chamber common to both of said passages, and means to deflect an air blast away from said vaporizing chamber.

5 In testimony whereof I hereunto affix my signature this 11th day of February, A. D. 1928.
